MANHOLE COVER LOCK

John J. Morris, Tuckahoe, and William C. Stohldreier, Bronxville, N. Y.

Application June 6, 1942, Serial No. 446,018

7 Claims.

(Cl. 292—6)

Our invention relates generally to improvements in manholes and analogous structures, and the same has for its object to provide a locking mechanism for securing the covers or lids in place which is simple in construction, easy to operate and efficient in use.

Further, said invention has for its object to provide means for securing the covers of manholes and analogous structures so as to prevent the unauthorized opening of the manhole or the removal of the cover by unauthorized persons.

Further, said invention has for its object to provide a locking device of the character specified which is carried wholly by the manhole cover or lid so that the said cover and locking device may be applied to or removed from the manhole as a unit.

Further, said invention has for its object to provide a cover with a locking mechanism which has substantially none of its parts extending above the upper surface thereof where the same might be subject to injury due to vehicular traffic passing over the road.

Further, said invention has for its object to provide a locking device of the character specified which will operate to clamp the cover of a manhole more securely in place when an unauthorized attempt is made to pry or otherwise remove the same from its locked position.

Other objects will in part be obvious, and in part be pointed out hereinafter.

To the attainment of the aforesaid objects and ends, our invention consists in the novel features of construction, and in the combination, connection and arrangement of parts hereinafter more fully described and then pointed out in the claims.

In the accompanying drawing:

Figure 1 is a plan or top view showing one form of manhole cover and locking means constructed according to, and embodying our said invention;

Figure 2 is a transverse section on the line 2—2 of Figure 1;

Figure 3 is an enlarged horizontal section on the line 3—3 of Figure 2;

Figure 4 is an enlarged detail side elevation of the parts seen in plan at Figure 3, and

Figure 5 is an enlarged detail top view illustrating a modified form of locking means including four locking arms and the bearings therefor.

In said drawing, referring to Figures 1 to 5, inclusive, 10 designates a manhole casting or frame of annular form having inwardly-tapering side walls 11 and a lateral flange 12 at its base for supporting the casting or frame 10 upon the masonry foundation 13 which lines the man-

hole. The casting or frame 10 is provided upon its inner side directly below its upper edge with an inwardly-projecting supporting flange 14 upon which is seated the usual manhole cover or lid 15. The upper side of the cover 15 is provided with short projections 16, a central recessed opening 17 to receive a bolt 18 which serves to support the locking device about to be described, and a circular series of air vents 17a.

10 The bolt 18 is provided with a threaded lower portion 18a, and a reduced intermediate portion 18b, which latter is embraced by a revoluble bearing 19 having fixed position upon the bolt longitudinally thereof. Below the bearing 19 is provided a threaded bearing 20 engaging the threaded portion 18a of the bolt 18, and at the extreme lower end of said bolt is a nut 21, securable to adjusted position by a pin or screw 22, to limit the movement of the bearing 20.

20 Between the bifurcated ends of the threaded bearing 20 are pivotally secured the inner ends of locking arms 23 whose outer ends are free and provided with transversely-roughened portions or teeth 23a to engage with the inner wall of the manhole casting when said locking arms 23 are adjusted to locking position.

25 24 denotes loop-shaped links having their inner ends pivotally secured to the fixed bearing 19, and their outer or lower ends similarly secured to the arms 23 adjacent their inner ends which are secured to the movable threaded bearing 20.

In Figure 5 is shown a modification in which the bearing 19¹ and the threaded bearing 20¹ are 30 severally provided with four ends 19a, and 21a to receive the inner ends of the four arms 23b which are operatively connected by links 24¹.

The operation of the device will be largely obvious from the foregoing description. It need merely be noted that when the cover 15 is to be secured in the opening of the manhole casting or frame 10, the supporting bolt 18 is first rotated counter-clockwise by means of a suitable key or tool inserted into the recess 18c of the bolt 18, and the threaded bearing 20 caused to travel downwardly upon the threaded portion of said bolt. By this operation the outer free ends of the locking arms 23 will be caused to rise and move inwardly towards the bolt 18, and permit of said ends to clear the inner edge of the flange 14 of the casting 10, and allow the cover to be seated upon the flange 14. Hereupon a bolt or pin, as for example, 26 shown in dotted lines at Figure 2, is inserted into one of the air vent openings 17a to engage with one or the other of the lock-

ing arms 23 to arrest the rotation thereof when the bolt 18 is turned clockwise to draw up the threaded bearing 20 thereon and cause the free ends of the arms 23 to assume a more horizontal or aligned position in which position the outer ends of said arms will firmly impinge upon the inner wall of the casting 10, and engage with the underside of the flange 14, and thus hold the cover 15 firmly clamped or wedged in position within the casting 10. The bolt or rod 26 may be withdrawn as soon as the ends of the arms 23 engage with the inner wall of the casting.

To remove the cover, it merely becomes necessary to reverse the operation above described.

It is to be noted that any attempt by an unauthorized person not possessing the proper key or tool to engage the recess in the head of the bolt 18, to remove the cover by prying the same open will only result in the more positive and effective engagement of the ends of the arms 23 with the walls of the casting 10, and with the underside of the flange 14, due to the wedging action of the arms 23, in becoming more nearly aligned.

It is also to be noted that while we have shown and described our invention in connection with a manhole and cover, that the same is not limited thereto, but is equally applicable to other forms or types of receptacles or containers.

Having thus described our invention what we claim and desire to secure by Letters Patent is:

1. A device of the character specified comprising a manhole frame, a cover for closing the same, and locking means for securing said cover in position within said frame, said locking means comprising a revolute vertical support suspended from said cover, a revolute member mounted in fixed position on said support, a bearing mounted on said support below said fixed member and movable upon said support longitudinally thereof, a plurality of locking arms each pivotally secured at its inner end to said movable bearing, and link members each pivotally secured at its inner end to said fixed bearing and its other end pivotally secured to one of said locking arms adjacent the inner pivoted end thereof, said vertical support, when rotated, serving to actuate said movable bearing to move the free outer ends of said locking arms into and out of locking engagement with the inner surface of said manhole frame.

2. A device of the character specified comprising a manhole frame, a cover for closing the same, and locking means for securing said cover in position within said frame, said locking means comprising a revolute vertical support suspended from said cover, a member revolutely mounted in fixed position on said support, a bearing on said support below said fixed member and movable upon said support longitudinally thereof, a plurality of locking arms each pivotally secured at its inner end to said movable bearing, link members each pivotally secured at its inner end to said fixed member and its other end pivotally secured to one of said locking arms adjacent the inner pivoted end thereof, and cooperating means arranged in part upon said revolute vertical support, and in part upon said movable bearing for causing said movable bearing to travel upon said vertical support when said vertical support is rotated and move the free, outer ends of said locking arms into and from engagement with the inner surface of said manhole frame.

3. A device of the character specified comprising a manhole frame, a cover for closing the

same, and locking means for securing said cover in position within said frame, a revolute support in said cover extending below the underside thereof, a bearing on said support and movable longitudinally thereof, locking arms pivotally secured at their inner ends to said movable bearing, a second bearing having fixed position upon but revolute with respect to said support and members severally connecting said last named bearing with said locking arms adjacent their pivoted ends; said revolute support, when rotated, serving to move the outer free ends of said locking arms into and out of locking engagement with the inner surfaces of said manhole frame.

4. A device of the character specified comprising a manhole frame, a cover for closing the same, and locking means carried by said cover; said locking means comprising a revolute actuating member depending from said support, a traveling bearing on said actuating member, a plurality of arms pivotally secured at their inner ends to said traveling bearing, a revolute member having fixed position on said actuating member above said bearing, means operatively connecting said arms with said fixed member for causing the outer ends of said arms to engage with said manhole frame upon rotation of said actuating member, and means for holding said arms against rotation upon said actuating member while manipulating the device.

5. A device of the character specified comprising a manhole frame, a cover for closing the same, and locking means carried by said cover comprising a member loosely disposed in said cover having a depending threaded portion, a threaded bearing working on the threaded portion of said depending member, a plurality of arms pivotally secured at their inner ends to said threaded bearing, a member having fixed position on said depending member and revolute with respect thereto, and means connecting said fixed member with said arms adjacent their inner ends; said first-named member, when rotated, serving to move the free ends of said arms into engagement with the manhole frame to hold said cover in locked position therein.

6. A device of the character specified comprising a manhole frame, a flange therein, a cover seated on said flange for closing said frame, and locking means carried by said cover comprising a member loosely disposed centrally within said cover having a depending threaded portion, a threaded bearing working on said depending threaded portion, a plurality of arms pivotally secured at their inner ends to said threaded bearing, a member revolutely mounted on said first-named member, and having fixed position relative thereto, and links connecting said revolutely fixed member with said arms adjacent their inner ends; said first-named member, when actuated, serving to cause the free ends of said arms to engage with the inner wall of said manhole frame and with the flange thereof to hold said cover locked in position within said frame.

7. A device of the character specified comprising a manhole frame, a cover-supporting flange therein, a cover seated on said flange, and locking means comprising a supporting and actuating bolt loosely disposed centrally upon said cover and having a threaded portion, said bolt having a reduced intermediate portion, a threaded bearing member working on the threaded portion of said supporting bolt means for limiting the travel of said threaded bearing upon said bolt, a plurality of arms pivotally secured at their inner ends to

75 of arms pivotally secured at their inner ends to

said threaded bearing member, a second member having fixed position upon said bolt and revolvably embracing the reduced intermediate portion thereof, and links connecting the member embracing the reduced intermediate portion of said bolt with said arms adjacent their inner ends; said supporting and actuating bolt serving to move the free ends of said arms into and out

5 of operative engagement with the manhole frame; the free ends of said arms being engageable with means insertable through said manhole cover for holding said arms against rotation when said bolt is rotated to operate the device.

JOHN J. MORRIS.
